INVENTOR

John W. Hays,
By J. B. Lawyer,
Attorney.

UNITED STATES PATENT OFFICE.

JOHN W. HAYS, OF ERIE, PENNSYLVANIA.

STEAM-CYLINDER LUBRICATOR.

SPECIFICATION forming part of Letters Patent No. 269,666, dated December 26, 1882.

Application filed October 24, 1882. (No model.)

To all whom it may concern:

Be it known that I, JOHN W. HAYS, a citizen of the United States, residing at Erie, in the county of Erie and State of Pennsylvania, have invented certain new and useful Improvements in Steam-Cylinder Lubricators; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification—.

15 Figure 1 being a central longitudinal vertical section of my improved lubricator, showing the plunger in one position; Fig. 2, a similar section of the lubricator, showing the plunger in another position.

20 Like letters designate corresponding parts in both figures.

My improved steam-cylinder lubricator depends for its action upon the variation of the steam-pressure in the cylinder itself—that is, 25 when the steam is under pressure in the cylinder, it forces the plunger of the lubricator-pump forward, and when the steam exhausts in the cylinder and the pressure against the plunger is relieved the said plunger is forced 30 back by a spring.

In the drawings, A represents the body or holder, in which is mounted my improved device for operating the lubricator-plunger by the alternate action of steam-pressure and a 35 spring. This holder is to be screwed into or otherwise attached to the engine-cylinder at or near one end thereof, so that its interior will communicate with the interior of the cylinder. The lubricator-plunger B has an enlarged portion or piston, a, working in the bore of the inner end of the holder, and provided with a packing, b, so as to fit steam-tight therein. Further outward in the said holder the plunger has an enlargement, c, 40 moving in the inner end of an enlarged cavity, d, of the holder A. The said cavity also contains a coiled spring, C, which bears inward

at one end against the plunger enlargement c, while its other end bears against a head or bush, D, which screws into the outer end of the holder more or less, and thereby adjusts the strength of the said spring, as may be necessary or desired. There is also another bush or bolt, E, which surrounds the plunger B and screws into and extends through the bush D and reaches beyond it nearly into the inner end of the cavity d. This bush or bolt E limits the outward movement of the plunger B, and by screwing it more or less into the cavity the length of the stroke of the plunger is varied at will. Fig. 2 shows the plunger at the end of its outward stroke, and Fig. 1 shows it at the termination of its inward stroke.

The lubricator-pump G is of ordinary construction, and is mounted upon any suitable support.

What I claim as new, and desire to secure by Letters Patent, is—

1. In a steam-cylinder lubricator, the lubricator-plunger B, extended out of the lubricator-pump into a holder, A, attached to and communicating with the interior of the engine-cylinder, and terminating with a piston to work in the said holder, in combination with a spring, C, mounted in the holder and pressing in a direction counter to the pressure of the steam in the cylinder, substantially as and for the purpose herein specified.

2. In combination with the spring C, mounted in the holder A, the bush or head D, screwing into the said holder A to adjust the force of the said spring, substantially as and for the purpose herein specified.

3. In combination with the plunger B, provided with an enlargement, c, the adjusting bush or bolt E, substantially as and for the purpose herein specified.

In testimony whereof I affix my signature in presence of two witnesses.

JOHN W. HAYS.
